J. K. O'Neil,

Double-acting Pump,

No 23,485,

Patented Apr. 5, 1859.

Inventor,
John K. O'Neil

UNITED STATES PATENT OFFICE.

JOHN K. O'NEIL, OF KINGSTON, NEW YORK.

PUMP.

Specification of Letters Patent No. 23,485, dated April 5, 1859.

To all whom it may concern:

Be it known that I, JOHN K. O'NEIL, of Kingston, in the county of Ulster and State of New York, have invented certain new and 5 useful Improvements in Pumps; and I do hereby declare that the following is a full and exact description thereof, reference being had to the accompanying drawings, making part of this specification, Figure 1 being 10 a side elevation of the pump; Fig. 2, a central longitudinal vertical section thereof; Fig. 3, a plan of the bottom of the upper casting; Fig. 4, a plan of the top or counterpart of the lower casting with valves attached; Fig. 5, a transverse vertical section of the pump in the plane indicated by the line $\alpha\alpha$, Figs. 1, and 2; Fig. 6, a view in perspective of one of the pistons, the upper piston head thereof, being removed to show 15 the interior arrangement; Fig. 7, a diagram showing the position of the parts that support the pump at the bottom of the well.

Like letters designate corresponding parts in all the figures.

20 In the construction of the pump body, my object is to produce a pump which can be furnished at a moderate cost, and which is, at the same time, effective and simple, not liable to get out of order, and can readily be 25 taken apart for inspection or repair. To accomplish these objects, the pump body is made of two castings, A, and B, which are fitted together by means of bolts passing through holes a, a , (Figs. 3, and 4,) and held 30 by nuts, suitable packing b , being placed between the castings to make the joints tight. The castings are formed as follows:

35 The bottom casting B, has a mouth c , opening into the middle of a water passage C, which extends the whole length of the pump, to the ports of the induction valves, whereby many impurities are at first excluded from the pump. A horizontal partition d , separates this passage from the water 40 passages D, D, above, the valve ports f, f , of the induction valves, being in the outer ends thereof. These water passages are separated from each other by a transverse partition g ; (Fig. 2,) and above them is another partition V, with openings i, i , therein, which allow a communication between the water passages and the piston cylinders above; and valve ports k, k , for the eduction valves, also open into the air-chamber.

45 The upper casting A, of the pump, consists of the cylinders E, E, of a double piston

50 pump, and air-chamber F, situated between them.

Half-ball valves L, L, are conveniently used for the induction valves, thereby economizing space, and, at the same time, securing all the advantages of the spherical valve. They may be secured to small metallic spring-hinges s, s , which extend inward toward the center of the pump, and are secured to the under side of the partition V, thereby offering a more open and uninterrupted passage for the water around the valves, and presenting less opportunity for the lodgment of obstructions. Ordinary ball 55 valves M, M, may be used for the eduction or air-chamber valves, retained in place by wires t, t .

An elevating pipe G, extends from the bottom of the air-chamber, upward, to the top 75 of the well, where it is suitably connected with the working fixtures H, (Fig. 1,) of the pump. There is an aperture l , (Figs. 1, and 5,) near the bottom of the air-chamber, provided with a valve I, for the purpose of 80 allowing the water to escape from the elevating pipe, when desirable, so as to prevent stagnation or freezing in said pipe. This valve is controlled by the following means:— It is situated within the air-chamber, as 85 shown in Fig. 5, and is fastened to a stem m , which passes through a guide n , its outer end being attached to a vibratory arm o , pivoted at its lower end to the pump.

A connecting arm p , is secured to the top 90 of the vibratory arm, by a stiff-knee joint, so arranged as to prevent the two arms straightening beyond a certain extent, substantially as represented in Fig. 5; and to the lower end of said connecting arm, is pivoted a 95 small rod q , which extends upward to the top of the well, and is secured to an eccentric K, or any equivalent device, for actuating it. By simply turning the eccentric so as to raise the rod q , the valve will be forced inward, as indicated by red lines in Fig. 5, and the water will escape from the air-chamber, and, by consequence, also from the elevating pipe. A small coiled spring r , or its equivalent, is used between the vibratory 100 arm o , and guide n , to keep the valve closed at all other times.

The pistons of the pump are actuated by two levers T, R, one vibrating in the operating fixtures H, at the top of the well, and 110 the other on the pump at the bottom of the well. These levers are connected by rods

S, S, as represented in Fig. 1, so as to keep them in parallel positions. Very small rods may be used for this purpose, (mere wires in fact,) since the lower lever is actuated by alternately drawing, instead of pushing, said rods. The piston rods N, N, are jointed at their upper ends to the lever R, and also jointed at their lower ends, respectively, to the pistons O, O, (Fig. 2.). The pistons 10 O, O, are made to serve as their own guides, and thereby allow the jointing of the piston rods thereto, by the following construction: Each piston has two piston-heads, provided with high, raised rims w, w, the inner edges 15 h, h, of which fit closely, but not tightly, in the cylinder, as shown in the drawings. Around the rims, except at said edges h, h, considerable space is allowed for the reception of the packing y, and coiled springs z, z, 20 which are located within the packing, and constantly press it outward against the side of the cylinders, without adding much to the friction of the pistons in the cylinders. The springs are placed on each side of a central 25 disk u, situated between the two piston heads, the edge of which reaches outward to the packing y, and they are always kept in place by the edges h, h, of the piston heads. The parts may be secured together 30 by a screw on the upper piston head, passing through central holes in the disk and lower piston head, and held by a nut. When thus arranged, with the edges h, h, resting against the side of the cylinder, and separated a con-

siderable distance from each other, the piston can be moved directly up and down without being liable to cant and bind in the cylinder, while the piston rods N, N, can incline in either direction without interfering with the free working of the pump. And 35 this is thus effected by a simple cheap and light construction.

This pump may be used either above or below the surface of the water; and a convenient means of locating it securely, is represented in Fig. 7, where it is fastened to cross-pieces U, U, the ends of which extend to the sides of the well.

I claim—

1. The combination and arrangement of the vibratory arms p, o, rod q, stem m, guide n, and spring r, for controlling the valve I, from the top of the well, substantially as described.

2. I also claim constructing the pistons O, O, with raised rims w, w, and guiding edges h, h, upon the heads thereof, in combination with the packing y, coiled springs z, z, and central disk u, arranged in the manner and for the purposes herein set forth.

In witness that the above is a true specification of my improved pump, I hereunto set my hand this — day of October, 1858.

JOHN K. O'NEIL.
